UNITED STATES PATENT OFFICE.

CHARLES MAXWELL STEVENSON, OF NEW BRIGHTON, NEW YORK, ASSIGNOR TO
STEVENSON ENGINEERING COMPANY, A CORPORATION OF NEW YORK.

PUMP.

1,057,986.

Specification of Letters Patent.

Patented Apr. 1, 1913.

Application filed December 21, 1911. Serial No. 667,118.

To all whom it may concern:

Be it known that I, CHARLES MAXWELL STEVENSON, a subject of the King of Great Britain, and a resident of New Brighton, in ⁵ the county of Richmond and State of New York, have invented certain new and useful Improvements in Pumps, of which the following is a specification.

This invention relates to improvements in ¹⁰ pumps.

Especially it relates to that class of pumps, wherein the pumping pistons both rotate and reciprocate; the reciprocation of the pistons being derived from their rotary ¹⁵ motion by the use of proper mechanism.

The present invention aims to produce a pump of the aforesaid class, having a simple and durable construction, which will not readily get out of order, will run for a ²⁰ long time without need of repair; will give a high duty, and which is so constructed that the various parts are readily accessible for renewal and repair.

The invention therefore particularly relates to the following, among other features, of construction: The rotary drum which contains said pistons is ported to provide a free radial inlet and discharge of fluids, and the fluid ports and channels are so arranged ²⁵ as to balance said drum. The mechanism for reciprocating the pistons is of such a character as to provide for free driving of the pistons, without binding or excessive friction. The lubrication of working ³⁰ parts is effective. Provision is made for readily assembling the several parts and for taking them apart when desired.

Other advantages of the invention, and the preferred form of parts embodying the ³⁵ several advantages, will be made clear by the description hereinafter following.

Referring to the drawings which accompany the specification, to aid the description, Figure 1 is a broken plan view on relatively ⁴⁰ small scale, showing, among other parts, the arrangement of the fluid passages to effect the balancing of the rotary drum. Fig. 2 is a longitudinal vertical section, on larger scale, of the pump on the plane of the line ⁴⁵ 2-2 of Fig. 1. Fig. 3 is a cross section and elevation on the plane of the line 3-3 of Fig. 1, but on large scale. Fig. 4 is a cross section and elevation on the plane of the line ⁵⁰ 4-4 of Fig. 1, but on large scale. Fig. 5 is a sectional detail of the

said drum, the spider retainer, and certain other parts. Fig. 6 is a detail, on small scale, indicating how the two parts of said retainer are brought together. Fig. 7 is a horizontal section and plan of the casing ⁶⁰ and the drum, the top of the casing being cut away and the drum being indicated in plan. Fig. 8 is an end view of the said retainer showing the oil groove and connecting groove. Fig. 9 is a broken sectional ⁶⁵ view of said universal joint. Fig. 10 is a cross sectional detail of a piston and other parts of said universal joint. Fig. 11 is a perspective view of one part of said drum.

The apparatus constructed in its various ⁷⁰ parts of suitable materials, is constructed and arranged as follows: The stationary casing 1, suitably supported is provided with bolted heads 2, 3; said head 2 being provided with the capped hollow boss 4 for ⁷⁵ the stem of the said spider retainer, and for lubricant, and said head 3 being provided with a suitable stuffing box 5, through which the main shaft 10 runs, and also provided with a bracket 6, having suitable bushings, ⁸⁰ for properly alining said shaft 10. Said bracket 6 is provided with lubricating chambers 7, and on said shaft 10 is a loose ring 8 dipping into the lubricant and aiding in lubricating said shaft 10. A screw plug 9 may ⁸⁵ be provided for drawing off the lubricant. Said shaft 10 is fitted into the drum 16 with a conical end, and is very rigidly secured to said drum by the aid of the lock nut 11 and key 19. Said casing 1 is provided with main ⁹⁰ inlet and discharge connections as 12, 13 respectively (Fig. 3), which are respectively connected with diagonal suction and discharge passages cast on said casing 1, and respectively indicated by 14, 15. The arrangement of said diagonal passages 14 and ⁹⁵ 15 will be clearly understood by comparing Figs. 1, 2, 3, 4 and 7 with each other; and the arrangement of said passages is such that said rotary drum 16 is balanced and ¹⁰⁰ runs with great smoothness and the minimum of friction even at the highest speeds, and the said arrangement of said passages is an important feature of my invention. Said casing 1 is also provided with dia- ¹⁰⁵ metrically opposite surfaces 20, 21, forming "seals" separating the inlet and discharge passages from each other. Fitted in said casing 1, with true running fit, is the rotary drum 16 fixed to and driven by said shaft ¹¹⁰ 110.

10. For convenience in assembling the parts of the machine, said drum 16 is made in two parts, as clearly indicated in Fig. 5, the two parts being secured together by longitudinal bolts. Said drum 16 is chambered longitudinally for the pistons 25, and is also chambered to admit the aforesaid retainer 35. (See Fig. 5.) The inner walls of said piston chambers are continuous except where said walls are perforated to permit the arms 24 of the spider 26 to pass through said walls and engage and reciprocate said pistons 25, and said walls seal said pistons inwardly against leakage. Said pistons 25 may be of any desired number, and are preferably arranged concentrically, and at uniform distances apart, around the axis of rotation, so as to aid in properly balancing said drum 16 when revolving at high speed. At the ends of said piston chambers, said drum 16 is cut away to form radial ports 18 for inlet and discharge of fluid from the said drum (Figs. 5 and 11). Said radial ports are clearly shown in plan view in Fig. 7, and are of material advantage in increasing the duty of the pump. The ends of the projecting parts of said drum have true working fit with the heads of said casing 1. Any suitable provision may be made for lubricating said drum 16 in said casing 1, and said drum may be provided with water seals. In each of said piston chambers reciprocates pistons 25 with true working fit. To properly reciprocate said pistons, with a minimum of friction, and without binding, the following construction is employed: In a cylindrical transverse hole 22, of each said piston is fitted, with true working fit, a through bored ring or plug 23, the bore whereof has nice working fit with the end of the arm 24, of a spider; the central ring part 26 of said spider having a nice working fit in the inclined groove of the aforesaid spider retainer 35; and said spider is provided with as many arms 24 as there are pistons 25, one arm for each piston; each of said pistons having a lateral conical bore 29 to admit of the entrance and working of its respective arm 24. The aforesaid construction provides an efficient universal joint between the said spider arms 24 and said pistons 25, whereby said pistons are reciprocated with a minimum of friction and without binding on said spider arms in said drum; and a universal joint in the means for reciprocating the pistons is an important feature of the invention. Said retainer 35 is preferably made in two parts for convenience in assembling, (Fig. 5); said parts being securely fastened together by the bolt 34, and one part of said retainer being provided with a tongue 33 and the other part being provided with a corresponding groove 43, to position the two parts of said retainer 65 accurately and rigidly together, (Fig. 6);

and the parts of said retainer may also be provided with dowels. Each half of said retainer 35 is provided with part of a groove and with part of a bearing or hub, and when the halves of said retainer 35 are secured together, there is formed a complete groove 36 for the spider ring 26 and a complete central hub or bearing 32 on which said spider revolves as an axis. The ring 26 of said spider is fitted accurately in said groove 36. Said retainer 35 is provided with a bearing 37, which has a nice working fit in the part 16^a of said drum 16. Said retainer 35 is also provided with the stem 38, which enters and is fixed stationary in said boss 4 of head 2, so that said retainer 35 remains stationary while said drum 16 revolves. Said boss 4 is provided with a space for lubricant, and said retainer 35 and its parts are provided with lubricating channels 39, 40, 41 for delivering the lubricant into said groove 36. Said spider arms 24 are also provided with lubricating passages 42, and thus lubricant is supplied to the various working parts of the mechanism which drive said pistons 16 and to said pistons.

The operation is as follows: Assuming the drum 16 to be driven by any suitable prime mover, as an electrical motor, and in the direction indicated by the arrows in Figs. 3 and 4, and that the pump suction is connected with a source of fluid supply, its discharge being connected with any suitable discharge pipe, then connection 12 (Fig. 3) will be the inlet, and connection 13, (Figs. 3 and 4) will be the discharge. Now, since said retainer 35 is stationary, but said drum 16 revolves and carries pistons around the axis of revolution along with said drum, and since the retainer groove 36 is inclined to the longitudinal axis of the said drum 16, it follows that said pistons 25 each acquire a reciprocating motion in their respective chambers in said drum 16, whereby, at any instant, each of said pistons is sucking fluid into one end of said drum, and is discharging fluid previously sucked in from the opposite end thereof. Thus said pistons produce a continuous suction of fluid in through said connection 12 and a continuous discharge of fluid out through said connection 13. As hereinbefore stated, said suction connection 12 is itself connected with a diagonal passage 14 carried around said casing 1, and said discharge connection 13 is itself connected with a discharge passage 15 carried around the other side of said casing 1, and on the opposite diagonal. Thus there are suction ports or passages 14 at opposite ends and opposite sides of said drum 16, and there are also discharge ports or passages at opposite ends and sides of said drum 16, and there results an excellent balance of said drum even at very high speeds, 13

whereby very smooth silent running of the pump and minimum of friction are induced. The said retainer groove and the said seals 20, 21 of said casing 1 are so arranged that 5 said seals are in line with the said pistons when at their positions of rest—that is, at the positions where their longitudinal motion in one direction has just ceased, and their longitudinal motion in the other direction 10 is just about beginning. For further explanation, assuming that the lower piston in Fig. 2 has been moving to the right and is near the end of its stroke, then fluid will have been sucked into the lower left-hand 15 end of the drum 16. At the same time, the upper piston will have been moving to the left and will be near the end of its stroke and fluid will have been also sucked in at the upper right end of said drum. But, as 20 aforesaid, there is a diagonal suction passage 14 around said casing connecting with respective chambers at the lower left, and the upper right ends of said drum 16. Simultaneously, said lower and upper pistons 25 will have been respectively discharging fluid from the lower right and the upper left end of said drum, and these ends are connected by the diagonal discharge channel 15. Thus there is continual suction and 30 continual discharge from the respective suction and discharge mains.

It will be understood from the foregoing description that the pump is double-acting, utilizing both ends of the plungers simultaneously, and producing as hereinbefore stated a perfect balance; that said pump is so constructed and arranged that all working parts are protected from contact with the water or other fluid operated on by said 40 pump; and that the lubricant can be supplied under pressure by screwing the cap on to the said boss 4 to the proper degree to produce any desired compression. On pumps of great capacity a force feed lubricating pump can be employed to supply the lubricant. The pump is also so constructed that the several suction and the several discharge ports are respectively so far independent of each other, that, as will be evident, by connecting said several suction ports with separate supply pipes for different fluids, and by connecting said several discharge ports with different discharge pipes, which may either deliver into the 50 same main discharge or into a common receptacle, the pump can be employed for mixing different fluids.

Now having described my improvements, I claim as my invention—

1. In a pump of the kind described, the combination of a rotary drum provided with a plurality of longitudinal cylinders having radial ports at the extremities of said drum, continuous reciprocating pistons in each of said cylinders, a stationary case within which said drum revolves with substantially water-tight working fit, and said case being provided with end peripheral ports at the extremities of said case adapted to register with said radial ports, and also provided with sealing surfaces between said peripheral ports, and rotary means in said stationary case operatively connected with said pistons to reciprocate the same, substantially as described. 75

2. In a pump of the kind described, the combination of a rotary drum provided with a plurality of longitudinal continuous cylinders having radial ports, reciprocating pistons in each of said cylinders, a stationary case within which said drum revolves with substantially water-tight working fit and provided with diagonally arranged end peripheral suction and discharge ports at opposite extremities of said case of such dimensions that each of said ports registers simultaneously with a plurality of said radial ports, spiral channels on the said case connecting pairs of diagonally opposite suction and diagonally opposite discharge ports together, heads on said case forming outer walls of said radial ports, and rotary means in said case operatively connected with each of said pistons to reciprocate the same, substantially as described. 90

3. The combination in a pump, of a rotary drum provided with suction and discharge cylinders having internal sealing walls, reciprocating pistons in said cylinders, a stationary case for said drum, a stationary retainer and rotary operative connections between said retainer and said pistons, and said casing, said retainer and said drum being provided with surfaces adapted to separate the suction and discharge passages, substantially as described. 100

Signed at New York city, in the county of New York, and State of New York this 20th day of December, A. D. 1911.

CHARLES MAXWELL STEVENSON.
